UNITED STATES PATENT OFFICE.

FREDRICH R. RADDATZ, OF OXFORD, NEW JERSEY.

BURIAL-CASE.

1,033,733.

Specification of Letters Patent. Patented July 23, 1912.

Application filed September 17, 1910. Serial No. 582,486.

To all whom it may concern:

Be it known that I, FREDRICH R. RADDATZ, a citizen of the United States, residing at Oxford, in the county of Warren and State of New Jersey, have invented certain new and useful Improvements in Burial-Cases, of which the following is a specification.

This invention relates to improvements in burial cases, and more particularly to those constructed of plastic material, such as cement, concrete or artificial stone formation and made into suitable molds designed for the purpose.

The object of the invention is to construct a burial case or sarcophagus that will be satisfying and ornamental in design, impervious to water and vermin, comparatively inexpensive to manufacture and practically imperishable and indestructible.

Another object of this invention is to provide metallic skeleton frames which are located within the walls of the body and top of the case, which frames are located within said parts in their formation, for strengthening the same and therefore rendering them more durable and better adapted to withstand the rough usage in shipping.

A further object of the invention is to provide a very simple, durable and effective means for lowering and handling the case within a grave and further, in providing means for fastening the cover on the case, said fastening means, together with the remaining metallic parts employed in the formation of the case, forming a continuous metallic construction.

Other objects and advantages will be apparent from the following description and it will be understood that changes in the specific structure shown and described may be made within the scope of the claim without departing from the spirit of the invention.

In the drawings: Figure 1 is a top plan view of the complete invention with the lid partially broken away, Fig. 2 is a side view of the case and cover with the outer wall partially in section, showing the metallic construction located within the wall, Fig. 3 is a vertical longitudinal section of the case, Fig. 4 is a horizontal longitudinal section of the same, Fig. 5 is an enlarged section of the screw threaded socket and frame attached thereto.

Referring to the drawings, 1 represents a box or case which is of suitable dimensions

and shape to freely receive an ordinary casket and 2 the cover for the same which when hermetically sealed in position upon the box, a practical underground vault is obtained, which according to its construction and plastic material employed in its formation constitutes an impervious inclosure for said casket. As previously stated the case or box is primarily constructed of a series of longitudinal metallic bars 3, and transversely arranged bars 4, which are arranged at predetermined distances apart and united at their intersecting portions by bolts or rivets 5, all the walls including the bottom for the case being likewise constructed and secured together in their relative position. The frame thus constructed is located within a suitable mold corresponding in shape to the frame thus constructed and the concrete, cement or other plastic material formed about said frame in the usual manner whereby solid walls including a bottom are formed inclosing or covering the metallic frame. In the formation of the box or case as above described, two ledges 6 are provided upon which the casket is adapted to rest when located within the box or case, whereby the usual ropes employed for lowering the casket within the box may be easily withdrawn from under the casket without further disturbing the same. Located within the cement walls of the box or case thus formed are screw threaded sockets 7, which are arranged at the corners of said box, the upper edges of which are substantially flush with the upper edges of the box, the lower surfaces of which are provided with right angular shaped grooves 8, which receive the meeting ends of the metallic frame adjacent to the upper edge of the box or case. In order to rigidly secure the screw threaded sockets 7 in their proper position in respect to the metallic skeleton frame, bolts 9 are passed through the lower ends of the sockets and through the meeting longitudinal bars 3, whereby the said bars are not only rigidly secured at that portion of the frame work, but are also connected in such a manner as to securely hold the said sockets in a binding and secure position within the cement side walls of the box.

The cover 2 for the box or case may be of any suitable design or ornamentation and is provided with an inner continuous flange 11, which is located at a suitable distance from the edges of the cover, the outer edges

of said flanged portion being snugly in contact with the inner walls of the case when the lid is in its proper position, said flange being formed or cast with the cover in the manufacture of the same. In casting the cover 2, longitudinal metallic strips or bars 12 and transverse bars 13 are located and arranged within its wall in a like manner to that previously described in reference to the skeleton frame provided for the case or box, for properly strengthening the said cover and rendering the same more durable for shipping and usage.

Secured to the corners of the top 2 are loops or staples 14 through which ropes are adapted to be passed for lowering the cover in its proper position upon the case, and by their construction the ropes employed may be easily removed in the usual manner.

20 In practice screw eyes 15 are first screwed into the screw threaded sockets 7, which provide means for lowering the box within a grave by suitable ropes after which said screw eyes may be removed and ordinary bolts 16 passed through suitable openings in the cover and into the screw threaded sockets 7 for finally securing the cover in its proper position upon the box, after which

the cover may be hermetically sealed in the well known manner.

What is claimed is:

A concrete burial case having a metallic frame work embedded therein, and end blocks embedded in the corners of the case, said end blocks having passages formed therein to receive the ends of the frame members and being formed with a threaded passage extending downward from the upper face of the block, and bolts passing through the blocks exterior to said threaded passage and transversely of the other passages and through the ends of the frame work to secure the frame-work in the passages in the block, the block projecting upward through the frame work and lying flush with the top of the case, whereby said blocks form both corner frame securing and bracing members and also provide sockets to engage the top securing device.

In testimony whereof I affix my signature, in presence of two witnesses.

FRED. R. RADDATZ.
